UNITED STATES PATENT OFFICE.

MATTHEW F. BRAMLEY, OF CLEVELAND, OHIO.

INCLINED-TRACK CONSTRUCTION.

1,149,623.

Specification of Letters Patent. Patented Aug. 10, 1915.

Application filed July 26, 1913. Serial No. 781,331.

To all whom it may concern:

Be it known that I, MATTHEW F. BRAMLEY, a citizen of the United States, residing at Cleveland, in the county of Cuyahoga and State of Ohio, have invented a new and useful Improvement in Inclined-Track Construction, of which the following is a specification, the principle of the invention being herein explained and the best mode in which I have contemplated applying that principle, so as to distinguish it from other inventions.

My invention is more particularly adapted for a looped inclosure having a racing track laid out thereon.

The object is the provision of a structure of the character implied which will safely as well as effectively preclude objects intended to travel rapidly about the inclosure encompassed thereby from being projected beyond the confines thereof.

The inventive conception involves the provision with an inclined track of a continuous fence of a flexible character yieldingly supported at the upper edge of the track so that should a racing vehicle rise along the track and actually engage the fence, the whole of the latter will yield and thereby take up the momentum of the vehicle. In consequence any serious shock is minimized, damage precluded and safety to both rider and spectators assured.

The inventive conception is embodied in means which are hereinafter explained and variously combined in the claims, while the annexed drawing and particular description thereof together set forth in detail one certain means constituting my invention, the disclosed means however, being but one of various mechanical forms in which the principle of my invention may be applied.

Referring next to the drawing: Figure I is a plan of a portion of a saucer-shaped track embodying my invention. Fig. II is a vertical section disclosing the conjunctive application of my improvement. Fig. III is an elevation of a given extent of the invention.

The exemplification depicted in the drawing is the adaptation of my invention to the upper or outer rim of a saucer-shaped track A, such as in vogue for the staging of motorcycle races. The edge of the sloping portion of the track A is held in position by a plurality of upright studs a' extending around the outer side of the same. Posi-

tioned just above the points of intersection of the track A with the inner edges of the studs a' are a corresponding number of wedge-shaped blocks a² which may be secured to the studs in any suitable manner not indicated. Extending between these blocks and hence around the track is a base-board construction a³, which is inclined inwardly at an obtuse angle with respect to the track A as clearly seen in Fig. II. Supported rearwardly around the track nearly on a level with the lower edge of the base-board a³, is an annular platform adapted to support tiers of seats a⁶ for the accommodation of the spectators.

A plurality of short pipe lengths B having their upper extremities provided with caps b', are affixed to the rear surface of the upper ends of the studs a' through the medium of a double set of bolts a². These pipe lengths project a given distance upwardly beyond the upper extremities of the studs a' and are provided just under their caps respectively with eye bolts b³ which have their nuts outwardly disposed. Suspended from each of the eye-bolts b³ is a short length of chain b⁴ to the free ends of each of which a screw-threaded member b⁵ is connected. The extremities of these members are formed as upwardly curved hooks b⁶. The screw-threaded portions of the members b⁵ each carry a pair of oppositely disposed nuts both designated as b⁷. Lying in the hooked extremities of the members b⁵, so as to extend around the track, is a cable C and this cable is preferably provided at regular intervals with turnbuckles c' whereby the extent of the cable may be shortened and the several chain lengths b⁴ drawn as taut as may be desired.

Clamped along its upper edge between the nuts b⁷ is a wire fence of any approved type of woven-wire construction. The weave should be close enough to afford the requisite strength and at the same time the desired yieldness. Along its lower edge portion this wire frame is clamped against base-boards a³ through the agency of a flat rigid facing d' which likewise abuts the surface of the track.

To be lamented is the fact that the inexperienced riders persist in venturing too high on the inclined portion of the track A, with a disastrous and frequently fatal result. Besides this however, the safety of the spectators warrants consideration, and

some provision for safety supplied which will not impair unto annoyance the view of the track. My inventive conception satisfactorily fulfils this want, by positively precluding a hurtling of either the rider or machine beyond the outer limits of the track.

My invention being thus described with sufficient thoroughness, what I desire to secure by Letters Patent and therefore claim specifically, is:

1. An inclined track construction comprising in combination an inclined curved track, a plurality of uprights continuing along the entire extent and projecting above the upper edge of said track, a fence connecting said uprights and disposed at an angle inwardly thereto, means for supporting the fence relative to the uprights, and a stiff facing for the lower portion of said fence, said means being yielding for the useful purpose specified.

2. An inclined track construction comprising in combination, a plurality of posts, a flexible fence secured below to said posts and projecting at an angle therefrom, an inclined track below such fence, suspension means yieldingly connecting the upper edge of said fence with said posts, and a stiff facing for the lower portion of said fence.

3. An inclined track construction comprising in combination, an inclined track arranged in a loop, posts positioned around and projecting above said track, a suspension member loosely connected with each such post, a flexible cable connecting said members, a correspondingly looped fence of flexible character interposed between said cable and posts, means for securing the lower edge of said fence to the track, and means for fixing the upper edge of said fence to said members.

4. An inclined track construction comprising in combination, an inclined circular track, a plurality of posts arranged therearound, a corresponding number of chains secured to said posts respectively, a cable connecting said chains, means for adjusting said cable to tauten said chains, and a flexible fence extending downwardly from said cable and secured to said posts.

5. An inclined track construction comprising the combination of a saucer-track; a flexible fence extending around and leaning inwardly from the upper edge of said track, a stiffening member secured to said fence ad-

jacent the track, and means yieldingly supporting the upper edge of said fence.

6. An inclined track construction comprising in combination with a saucer-track; of a plurality of supports disposed around and extending above said track, a flexible fence yieldingly connected with said supports and sloping toward said track, and facings on opposite sides of the lowest portion of said fence and abutting said track, said facings being secured to said supports.

7. The combination with a speed track having banked portions, of a safety guard therefor comprising a yielding net-work adapted to be applied to the upper portion of said track, a support above the upper portion of said track, and means flexibly connecting the upper portion of said guard with said support.

8. An inclined track construction comprising in combination an inclined arcuate track, a flexible fence having its lower edge secured along and leaning over the upper edge of said track, and means for yieldingly supporting the upper edge of said fence in an elevated position, a lower portion of such fence being rigid, the upper part of such fence being yielding.

9. An inclined track construction comprising in combination an inclined curved track, studs projecting above the upper edge thereof, a flexible fence attached near the upper edge of said track and leaning over the entire surface thereof, and means yieldingly connecting said fence with said studs.

10. An inclined track construction comprising in combination an inclined circular track, a fence of flexible character having its lower edge conforming to the upper edge of said track and secured thereto, such fence leaning over said track, and means yieldingly supporting the upper edge of said fence outwardly with respect to said track.

11. A safety guard for banked speed tracks or racing saucers comprising an elongated flexible net-work adapted to be applied to the outer margin of said inclined track or saucer and having its upper edge contracted or of less diameter than its lower edge, and means for yieldingly supporting the upper edge of said net-work.

Signed by me, this 19th day of July, 1913.

MATTHEW F. BRAMLEY.
